(No Model.)

J. B. LITCHMAN.
SHOE MAKER'S JACK.

No. 331,414.

Patented Dec. 1, 1885.

WITNESSES.

John Dennis
T. F. Reynolds

INVENTOR.

John B. Litchman

UNITED STATES PATENT OFFICE.

JOHN B. LITCHMAN, OF MARBLEHEAD, MASSACHUSETTS.

SHOE-MAKER'S JACK.

SPECIFICATION forming part of Letters Patent No. 331,414, dated December 1, 1885.

Application filed June 26, 1885. Serial No. 169,817. (No model.)

To all whom it may concern:

Be it known that I, JOHN B. LITCHMAN, of Marblehead, in the county of Essex and State of Massachusetts, a citizen of the United States, 5 have invented a new and useful Improvement in Shoe-Makers' Jacks, of which the following is a full, clear, and exact description, reference being had to the accompanying drawings, forming a part of this specification, in explaining its nature.

This improvement relates to the way of constructing and mounting a jack, and also to the way of fastening a last to the jack, and it produces a jack which is adjustable in any direction, has a straight instead of a curved shank, 15 as is usual with jacks, and from its construction it can be used either as a right or left hand jack.

The method of locking the last upon the 20 jack also presents some advantages.

In the drawings, Figure 1 is an elevation of the jack, showing its connection with a bench, and in the same figure the dotted line shows the position of the same jack connected with 25 a table on the left-hand side of the drawing, instead of the right-hand side, as shown by the full line, and illustrates what is meant by the phrase "right-hand" and "left-hand" jack. Fig. 2 shows the vertical joint of the jack in 30 section. Fig. 4 is a slightly varied form of the vertical joint. Fig. 3 is a form of the vertical joint which has some disadvantages which the form shown in Figs. 2 and 4 are intended to obviate. Fig. 6 is a view of a modified form of a part or plate, hereinafter referred to. Fig. 5 is a plan view of the last.

A is the bench. An arm, B, is attached to this bench in any proper position, and on this arm is fixed an ear, b, between which ear b and 40 the arm B is made the vertical joint by which the shank of the jack is adjusted at any desired angle with the arm B. The socket C has on one side two ears, c c, through which the shank D of the jack is passed, and on the other side of 45 the socket C is another ear, c', which makes, with the arm B and its ear b, a vertical joint, around the horizontal pivot of which the jack may be moved into any angle with the horizon lying in the same vertical plane. The shank 50 D of the jack is made with a shoulder, d, that rests upon one of the ears c, and when it is

desired that the jack shall be a left-hand instead of a right-hand jack the collar d', which is at the lower termination of the shank, may be taken off and the jack reversed, as shown 55 in dotted lines in Fig. 1, or by removing plate C and reversing it. On the upper part of the shank D is a pintle, E, which enters a hole in the body of the last. Toward the heel of the last F, in the upper part of it, is made a 60 square hole or mortise, f, which is covered by a metallic plate, g. To an ear, h, on one side of the shank D is hinged a spring-latch, i i', which is formed at its end to lock behind the plate g, and so fasten down the last upon the 65 jack.

If the vertical joint of this jack were made in the way in which it is usual to make clamp-joints, as shown in Fig. 3, the tightness of the joint would depend upon the spring that can 70 be given to the arm B or ear b, or both; but my improvement consists in forming in the ear b a cavity for the passage of the bolt k considerably larger than the size of the bolt, and inserting in this cavity a ferrule or sleeve, 75 m, which may be rigid, as shown in Fig. 4, or a spring, as shown in Fig. 2, by which the pressure of the nut l, when it is turned up, is brought to bear, not against the ear b to spring it sidewise, and so clamp it upon the ear c', 80 but against the ear c' itself, and so clamp it directly against the arm B.

The drawings show the washer b' interposed between the ear c' and the arm B; but this is not a matter of absolute necessity. If a spring 85 is used instead of a ferrule, as in Fig. 4, it is desirable to have a washer, l', Fig. 2, between the nut l and the spring.

It will be observed that with this form of jack no toe support is needed, and that therefore the breaking of the upper across the vamp is prevented. It will also be observed that on account of the peculiar construction of the jack there is no liability of breaking the quarter as it is drawn over the last between the under surface of the last and the upper surface of the jack-support. 95

I would say that the last may be made of cast-iron instead of wood, in which case the recess or hole f and its covering-plate will be 100 formed in casting.

The socket or socket-plate C, instead of be-

ing made and shaped as shown in Fig. 1, may be shaped to bring the upper ear, *c*, below the hole in the ear *c'*, through which the bolt or pivot connecting it with the arm or support *B* extends; and on some accounts I prefer this construction, as it brings both bearings of the shank *D* below the center or pivot *k*, and I am thereby enabled to more firmly and securely hold the jack in a vertical position. When this form of socket-piece is used, it will be observed that the last, when the shank *D* is turned horizontally, will be brought into substantially the same position or plane that it occupies when in a vertical position, which I consider to be a material advantage. It also enables me to make the device more compact and to operate it in less space.

It will be seen that the last used with the jack is of peculiar construction, and that it has one hole for the reception of the pintle or spindle which is like the hole with which lasts are generally provided, with the exception that it is a little farther forward and, in addition to this hole, that it has a locking hole or recess which is adapted to receive the end of the latch or lock in such a manner as to enable the same to hold the last fastened down upon the pin; consequently the recess or space must be under cut and must be covered with a plate. If the last is of cast metal, then the recess can be of proper shape and can be formed in casting; but if made of wood, it will be necessary to form therein holes, substantially as shown in Fig. 1, and to cover the same with a metal plate, *g*, having holes shaped substantially as represented in plan in Fig. 5.

The state of the art prior to this invention may be understood by patents to Mawhinney, of November 15, 1881, No. 249,651, and to Plummer, April 6, 1869, No. 88,735.

Having thus fully described my invention, I claim and desire to secure by Letters Patent of the United States—

1. The combination of the arm *B*, provided with an ear, *b*, with the shank of a jack, *D*, adapted to pass through the socket-piece *C*, having the ears *c c'*, substantially as described.

2. In an adjustable shoe-maker's jack, the clamp-joint composed of the members *B*, *b*, and *c*, combined together by means of the nut and bolt *k l* and sleeve *m*, substantially as described.

3. The combination, with the shank *D* of a jack, of the pintle *E* and spring-latch *i i'*, for the purpose of locking the last to the jack, substantially as and for the purposes described.

4. In combination with the latch attachment of a pegging-jack, a last having a hole for the pintle, and a locking-recess behind the same of the character described, substantially as and for the purposes set forth.

5. In combination with the latch attachment of a pegging-jack, the last provided with a metal plate, *g*, having holes formed therein, as described, all substantially as and for the purposes set forth.

JOHN B. LITCHMAN.
